[57] CLAIM

The ornamental design for a combined body composition measurer and cover therefor for determining body fat, as shown and described.

DESCRIPTION

FIG. 1 is an exploded perspective view of a combined body composition measurer and cover therefor for determining body fat;

FIG. 2 is a top plan view thereof;

FIG. 3 is an exploded side elevational view thereof; and
FIG. 4 is an exploded end elevational view, the opposite
side being identical thereto.

FIG. 2

FIG. 3

FIG. 4
